US0D1102343S

(12) **United States Design Patent** (10) **Patent No.:** **US D1,102,343 S**
(45) **Date of Patent:** **** Nov. 18, 2025**

(54) **VEHICLE WHEEL RIM**

(71) Applicant: **NIO TECHNOLOGY (ANHUI) CO., LTD**, Hefei (CN)

(72) Inventors: **Kris Tomasson**, Munich (DE); **Armin Hobrücker**, Munich (DE); **Joonyoung Koo**, Munich (DE); **Mostafa Bonakdar**, Munich (DE); **Karl Huang**, Shanghai (CN); **Nianzhong Chen**, Shanghai (CN); **Qifeng Gao**, Shanghai (CN); **Arturo Peralta**, Munich (DE)

(73) Assignee: **NIO TECHNOLOGY (ANHUI) CO., LTD**, Hefei (CN)

(**) Term: **15 Years**

(21) Appl. No.: **29/946,018**

(22) Filed: **Jun. 6, 2024**

(30) **Foreign Application Priority Data**
